Des. 203,498
Patented Jan. 18, 1966

203,498

CONVERTIBLE CARGO COVER OR SIMILAR ARTICLE

Ralph C. Young and Richard T. Bingman, El Paso
County, Colo., assignors to White Automotive Corporation, a corporation of Colorado

Filed Oct. 14, 1963, Ser. No. 76,966

Term of patent 14 years

(Cl. D14—27)

Fig. 3

We claim:

The ornamental design for a convertible cargo cover or similar article, as shown and described.
